AUTOMATIC TEMPERATURE REGULATOR

Filed Nov. 2, 1927

UNITED STATES PATENT OFFICE

ANDRÉ CHAGNAUD, OF PARIS, FRANCE, ASSIGNOR TO LES ETABLISSEMENTS POULENC FRERES, A CORPORATION OF FRANCE

AUTOMATIC TEMPERATURE REGULATOR

Application filed November 2, 1927, Serial No. 230,576, and in France November 3, 1926.

The present invention relates to automatic temperature regulators and, more particularly, to those of the type having a galvanometric control.

- 5 One of the objects of the invention is to improve the form of contacts controlled by the galvanometer needle and leading to the heating circuit so as to increase the sensitivity and reliability of the control device.
- 10 A further object is to provide a galvanometrically controlled regulator capable of being connected to any ordinary lighting circuit and operating correctly even when vibrated.
- 15 Still further objects will appear in the course of the detailed description now to be given with reference to the accompanying drawings, in which:

Fig. 1 is a diagram showing the galvanometer needle and an oscillatable control bar forming part of the device;

Fig. 2 is a diagram of one form of a make-and-break device forming part of the invention, the relays being omitted but the relay terminal connections being indicated by the arrow heads; and

Fig. 3 is a diagram of a modified form of make-and-break device connected to the "locking" circuits designed to prevent a second closure of the heating circuit until other operations to be described first take place.

Referring to the various figures of the drawing, there is shown a needle A forming part of a galvanometer (not shown) which is connected in circuit with a thermoelectric couple located in a chamber, or in contact with a material, whose temperature is to be regulated. B is a bar of substantially U-shaped formation positioned in parallel relation to scale or dial P of the galvanometer and capable of oscillating about $x-x$ as an axis. Bar B carries a fixed stud f'' for cooperating with contact f formed of suitable resilient material and carried by the dial P or in any other suitable manner so as to be normally held out of contact with the contact f'' fixed to the dial when f'' is not bearing on f , but adapted to close contacts f and f' when bar B lowers sufficiently to cause f'' to press downwardly on f , and a movable contact G''

comprising the contacts g and g' (g being formed of resilient material similar to f and being fixed to G in any suitable manner to be normally held out of contact with g'), G'' being capable of being displaced along the bar. Contacts f and f' control the devices that close the heating circuit, while contacts g and g' function to open said circuit or to diminish the amount of heat being supplied. By moving contact G'' along bar B, any desired limit of temperature may be obtained. Bar B is maintained in continuous oscillation by a vibratable bimetallic strip L to be described later which bears against the free extremity B' of bar B and lifts the portion of the latter carrying the contacts or else permits it to drop by its own weight. During its downward movement bar B closes the circuits without vibration. Obviously, the action of gravity may here be replaced by that of a spring or of an electromagnet. When the "too hot" contact G'' bears on a small cone A' mounted on needle A, contacts g , g' close. When cone A' moves away from the "too hot" contact G'' , i. e. when the needle moves into the "too cold" region, bar B is capable of moving further downward and will thus close the "too cold" contacts f and f' . The needle is prevented from moving beyond the "too hot" contact by a stop a .

Contact G'' carries a small knife-edge S on its lower side against which cone A' of needle A may slide and which insures proper sensitiveness for the device. If during downward movement of bar B cone A' is under knife-edge S, it will have to slide either to the right or to the left, i. e. it will either close the "too hot" contacts g , g' or permit closure of the "too cold" contacts f , f' to take place. The position of knife-edge S, therefore, determines the constant temperature control. The position of the contacts themselves becomes secondary importance. The "too cold" contacts f , f' may, consequently, be removed to a distance and rendered fixed.

In prior devices of the present type, temperature control has been obtained by permitting the galvanometer needle to abut against one or the other of pair of "too hot" and "too

“cold” contacts mounted in the path of movement of the needle. The opening and closure of the heat control circuits in such constructions is uncertain and unreliable and the least vibration suffices to disturb the accuracy of temperature control.

In the present construction, as above described, this uncertainty and unreliability are done away with. The various contacts are made positively and under pressure and there is, therefore, no possibility of error. Contact f' is fixed and incapable of movement, while contact G'' only causes an insignificant movement of needle A when the base of cone A' rests on graduated dial P. Needle A, it will be noted, is incapable of being distorted and its bearings will, therefore, remain intact indefinitely.

The system for moving bar B consists of a bimetallic strip L, fixed at one extremity M and inserted inside a resistance E connected to a source of current (independent of the pyrometer circuit) through the intermediary of a relay such as is shown in Fig. 3. The free extremity 1 of strip L moves upward or downward (according to whether current flows or does not flow through resistance E and whether the metal that has the greatest coefficient of expansion is on the top or bottom of the bimetallic strip) between a pair of contacts 2, 3 whose position may be adjusted.

In the spring form of intermediary connection between the strip L and the bar extremity B', shown in Fig. 2, the bimetallic strip L is positioned to deform upwardly when heated and counterweight H is placed as shown in Fig. 1. However, in the form shown in Fig. 3, the strip L is positioned to deform downwardly when heated and counterweight H is placed on the opposite side of the axis $\omega-\omega$ from its position in Fig. 1, that is, it is slid on B' forwardly so that the counterweight always tends to close the contacts connected to terminals F, F' or G, G', as the case may be, and deformation of L tends to open them. In this latter form contact 2 is connected to the master relay or locking system shown in Fig. 3 at the terminal F_A , contact 3 being connected at G'_A , and the stationary end of the strip M being connected at F'_A . Heating coil E is connected across ω_A , ω'_A and the source of control power is connected to ψ_A , ψ'_A .

In the form shown in Fig. 2 the connections for the heating coil and the bimetallic strip are the same as in Fig. 3 except that contact 2 is connected at G'_A , and contact 3 is connected at F_A because in this form of construction the strip L is positioned to deform upwardly when heated.

Extremity 1 will, it is evident, oscillate back and forth slowly and this slowness will be determined by (1) the elasticity of the strip L, (2) by the amount of current flowing through E, (3) by the resistance of the lat-

ter, and (4) by the distance between 2 and 3. Extremity 1 either bears against the free end B' of bar B to raise the latter or releases the bar and permits it to rest on the control contacts. If desired, the alternate contact of 1 with 2 and 3 may be utilized to actuate one or a pair of electromagnets properly positioned to actuate bar B.

If the circuit used for actuating the various regulating elements is to be the same as that used for heating resistance E, the wires may be properly connected to give the result desired.

The “locking” system shown as part of Figure 3 consists of a pair of feed terminals ψ , ψ' ; a pair of terminals ω , ω' connected to regulating or other devices to be controlled (resistances and the like) a magnet 23, acting on a bar 21 whose free extremity is arranged to engage with the bar 22 of another electromagnet 24. Bar 21 tends to move away from 23, while 22 has the same tendency relatively to 24. Terminals F' and G' are connected to g and g' respectively which are controlled by the galvanometer needle in the manner already described; one contact g is common to both terminals F' and G.

If the chamber or article whose temperature is to be regulated is too cold, needle A swings to the left (Figs. 1, 2 and 3) and contact f , f' is established. Bar 21 is then either free or interengages with bar 22. In the event that it is free, it contacts at 17, closes circuit ψ , ψ' , F', F, 23, 17, 21, ψ , excites magnet 23, which attracts bar 21, thus making contact at 16 and closing the circuit ψ , 21, 16, ω controlling the various heating elements. Bar 22 of magnet 24, being normally held away from magnet 24 when the said magnet is not excited, has a shoulder formed on its outer extremity which engages bar 21 of magnet 23 as bar 21 contacts with 16, thereby locking it in this position. Now, as the temperature of the devices which this mechanism controls increases, the needle A swings to the right and contact g , g' is established due to the deformation of the bimetallic strip L caused by the heating coil E. This heating coil is connected at ω_A , ω'_A of a second relay or locking system called the master relay of the bar, which is a duplicate of the first mentioned locking system called the regulating relay, which is connected to terminals F, F' and G, G'. When contacts g , g' are closed, magnet 24 is energized through circuit ψ , 21, 16, 24, G' , G, ω' , ψ' , the source of power being connected to ψ , ψ' . This energizing of magnet 24 causes the magnet to attract bar 22 which releases bar 21 and opens the circuit 16, and this causes the heating control mechanisms connected at ω , ω' to diminish or completely shut off the heat in the system. Thus it will be seen that any sparking due to opening and closing the power circuits is taken at the contacts 16 and 17 and not at the con-

tacts f, f' and g, g' on the galvanometer, this being one of the many distinct advantages over the ordinary form of control devices of this type.

3 The structures connected to ω, ω' for heating do not begin to function if g, g' is closed; thus, a plurality of successive contacts at g, g' will not cause any trouble. In the same way repeated contacts at f, f' will have no effect until contact g, g' is made. The part of the device operates, therefore, in the manner of a "locking" or "safety" system.

The operation of this system is as follows: Assuming the heating system being controlled by this invention is too cold (taking for example the form of construction shown in Fig. 3, the strip L straightens to its uppermost position and allows bar B to lower, and needle A, being in a position toward the left of the scale indicating low temperature, it allows contacts f, f' to close under the action of the counterweight H (H being on the forward side of axis $x-x$ in this form of the device). This causes the regulating relay to energize magnet 23 momentarily, which in turn attracts bar 21 and locks it in contact with contact 16 by virtue of the latching of bar 22 over bar 21. This energizes the control mechanisms connected to ω, ω' which in turn start up the heating system or other device. Now, while these operations are taking place (it being understood that strip L is in its uppermost position) the free extremity 1 of strip L contacts with 2, which energizes magnet 23' of the master relay, locking bar 21' into contact with 16' and energizing the heating coil E connected to ω_A, ω'_A . The strip begins to deform downwardly and raises bar B opening contacts f, f' without 40 sparking (since the regulating relay is still locked closed) and needle A begins to move to the right, indicating rising temperature in the heating system. After strip L is heated sufficiently by coil E to cause 1 to contact with 3, the master relay magnet 24' operates to release bar 21' and open the circuit of the heating coil E, now allowing strip L to straighten out again, which causes B to descend. During this time the heating system 45 is still turned on and the needle has now moved under the contacts g, g' or sufficiently far to cause S to engage A' and force the needle under the contacts. By this time the bar B will have descended far enough to cause contacts g, g' to close, which causes magnet 24 of the regulating relay to release bar 21 and open the control circuit for the heating system, thereby shutting off the system. As the cooling continues needle A swings slowly 50 toward the left and strip L continues to straighten until contacts f, f' close and 1 contacts with 2 again, and the whole cycle of opération is repeated.

The operation of the form of construction 55 as shown in Fig. 2 can readily be followed

from the preceding explanation applicable to Fig. 3, remembering that in Fig. 2 the strip deforms upwardly to lower bar B as before, but the closing of contacts 1 and 3 causes heating coil E to be energized to subsequently cause the strip to deform upwardly.

It will, of course, be obvious to those skilled in the art that lamp controls which respond to heating and cooling operations may be associated with the foregoing apparatus and that the apparatus may be used in any situation where a motor or similar machine is to be operated or stopped in accordance with the reading of a galvanometer or similar indicating instrument.

Having now particularly described and ascertained the nature of my said invention, and in what manner the same is to be performed, I declare that what I claim is:

1. In a device of the class described, an instrument indicating needle, a circuit having elements therein capable of doing work, oscillatable means operable in conjunction with said needle to control the opening of said circuit, and means operable by the said oscillatable means for closing said circuit when out of contact with the needle.

2. In a device of the class described, an instrument indicating needle, a circuit having elements therein capable of doing work, oscillatable means operable in conjunction with said needle to control the opening and closing of said circuit, and thermally controlled means for controlling the oscillation of said oscillatable means.

3. In a device of the class described, an instrument indicating needle, a circuit having elements therein capable of doing work, an oscillatable bar, spaced contacts associated with said bar and operable to open said circuit by bearing on said needle to cause said contacts to engage each other, and means for oscillating said bar.

4. In a device of the class described, an instrument indicating needle, control circuits having elements therein operable to control heating elements, an oscillatable bar, a fixed contact element and a movable contact for said control circuits mounted on said bar, said movable contact being adapted to contact with said needle, and means for oscillating said bar.

5. In a device of the class described, an instrument indicating needle, an instrument dial, a fixed control contact associated with said dial, an oscillatable bar, a fixed contact mounted on said bar opposite said fixed contact for the dial, a pair of contacts adjustably mounted on said bar, one of said contacts being positioned so as to be able to contact with said needle during oscillation of the bar, and means for oscillating said bar.

6. In a device of the class described, an instrument indicating needle, a pair of circuits controlling a heating element, an oscillatable

- bar, a fixed contact associated with said bar and operable to control one of said pair of circuits, a pair of movable contacts mounted on said bar and connected to the second of 5 said pair of circuits, one of said movable contacts being positioned so as to be able to contact with said needle; means for oscillating said bar, and means for preventing a second closure of one of the pair of circuits until 10 the other circuit is first opened.
7. In a device of the class described, a bar oscillator comprising a bimetallic strip fixed at one end and carrying a contact at the other end thereof, a resistance wire positioned near 15 the strip, a pair of contacts positioned on opposite sides of the contact carried by the strip, and means operable to cut off the flow of current to said resistance wire.
8. In a device of the class described, an instrument 20 indicating needle, a circuit having elements therein capable of doing work, a circuit closer included in said circuit, and oscillatable means operable to actuate the circuit closer for effecting a closing of the 25 circuit when the needle is out of coacting relation with the oscillatable means, said oscillatable means being adapted to coact with the needle without passing current through said needle to effect breaking of the circuit established by said circuit closer.
9. In a device of the class described, an instrument indicating needle, a circuit having elements therein capable of doing work, circuit closing means in said circuit, an oscillatable means to actuate the circuit closer when the needle is in one position, said needle in another position coacting with said oscillatable means without passing current through said needle to break the circuit established by said circuit closer, and means for controlling the oscillation of said oscillatable means.
10. In a device of the class described, an instrument indicating needle, a circuit having elements therein capable of doing work, circuit closing means in said circuit, an oscillatable means to actuate the circuit closer when the needle is in one position, said needle in another position coacting with said oscillatable means without passing current through said needle to break the circuit established by said circuit closer, and thermally controlled means for controlling the oscillation of said oscillating means.
11. In a device of the class described, an instrument indicating needle, a circuit having elements therein capable of doing work, including circuit closing means, circuit breaking means, and a member coacting with the circuit closing means to close the circuit aforesaid in one position of the needle and in another position of the needle to coact with the circuit breaking means to interrupt said circuit without passing current through said needle.
12. In a device of the class described, an instrument indicating needle, a circuit having elements therein capable of doing work, a circuit closer for said circuit, independent 70 circuit breaking means for interrupting said circuit, oscillatable means for effecting closing of the circuit through said circuit closer in one position of the needle, and for interrupting the circuit through said circuit breaking means under the control of the needle, without passing current through said needle, a thermally controlled device, and an auxiliary circuit in which said thermally controlled device is included operable incident to the interruption of the first mentioned circuit.
13. In a device of the class described, an instrument indicating needle, a pair of circuits for controlling a heating element, an oscillatable bar, a fixed contact associated with said bar and operable to control one of said pair of circuits, a member slidable on said bar and carrying a pair of contacts operable to control the other of said pair of circuits, 85 said pair of contacts being adapted to engage each other incident to movement of the indicating needle therebeneath and lowering of said oscillatable bar to exert pressure on said contacts by the said needle, and means 90 formed on said slidable member and said needle for deflecting said needle incident to lowering of the slidable bar when the needle is in a zone immediately adjacent to the pair of contacts carried by said slidable member. 95
14. In a device of the class described, an instrument indicating needle, a pair of circuits for controlling a heating element, an oscillatable bar, a fixed contact associated with said bar and operable to control one of said pair of circuits, a member slidable on said bar and carrying a pair of contacts operable to control the other of said pair of circuits, said pair of contacts being adapted to engage each other incident to movement of the indicating needle therebeneath and lowering of said oscillatable bar to exert pressure on said contacts by the said needle, and means formed on said slidable member and said needle for deflecting said needle incident to lowering of the slidable bar when the needle is in a zone immediately adjacent to the pair of contacts carried by said slidable member, said means comprising a knife edge 105 on said slidable member and a conical member carried by said needle. 110
15. In a device of the class described, an instrument indicating needle, a circuit having elements therein capable of doing work, including circuit closing means, circuit breaking means, and a member coacting with the circuit closing means to close the circuit aforesaid in one position of the needle and in another position of the needle to coact with the circuit breaking means to interrupt said circuit without passing current through said needle.

In testimony whereof I affix my signature.

ANDRÉ CHAGNAUD.
